United States Patent Office

Des. 177,437

Patented Apr. 10, 1956

177,437

TEAPOT

Viktor Schreckengost, Cleveland, Ohio, assignor to The Salem China Company, Salem, Ohio, a corporation of Ohio

Application April 7, 1955, Serial No. 35,402

Term of patent 14 years

(Cl. D44—26)

I claim:

The ornamental design for a teapot, as shown.
